APPARATUS FOR MIXING DENTAL CEMENT

Norton L. Wheeler, Tulsa, Okla.

Application May 20, 1943, Serial No. 487,799

8 Claims. (Cl. 259—1)

This invention relates to an apparatus for mixing dental cement and more particularly to the mixing of dental cement in air-conditioned receptacles.

The principal object of the present invention is to provide for the mixing of cement under proper temperature and humidity conditions.

It has long been the practice to use cold instruments, especially chilled mixing slabs, in mixing dental cement. It is also well known that the use of chilled instruments, when used with either the oxyphosphate and silicious cements, produces a set cement of superior properties than when uncooled instruments are used. Less haste is necessary in the mixing procedure and application of the cement to the teeth in the dental operation.

In offices having high temperatures, especially in the summer, and in localities having arid climates, the cement dries too much and too rapidly for proper cement manipulation. This is caused by the chilled slab becoming warm too quickly and the evaporation effected by the arid atmosphere. Furthermore, in humid climates, and in offices heated by open gas stoves, using natural hydrocarbon gas, the atmospheric moisture may condense upon the previously chilled slab, which condensate, in turn, would be mixed with the cement with detrimental results.

I have found that by enclosing the chilled slab during the mixing of the cement thereby decreasing the interchange of radiant heat, and maintaining low slab temperatures for a much longer period of time, and by various methods of conditioning the enclosed atmosphere around the slab, the precipitation of moisture upon the slab is eliminated and the drying of the cement is controlled.

Other objects of the invention are, therefore, to provide for enclosing a chilled dental cement mixing slab for reducing interchange of radiant heat; to provide a mixing receptacle having transparent panels for the chilled slab for permitting observation of the mixing operations; to provide the receptacle with a diaphragm panel permitting access with and operation of mixing tools for performing the cement mixing operation; to provide for quick access to and removal of the mixing slab from the receptacle; to provide for conditioning the air in the receptacle; to provide for dehydrating or humidifying the air in the receptacle according to the climatic conditions; to provide for agitating the air in the receptacle; to provide a sturdy, durable and efficient apparatus for the mixing of dental cement; and

to provide improved structural elements and improved arrangements thereof for providing proper conditions for mixing of dental cement.

In accomplishing these and other objects of the present invention, I have provided improved details of structure, the preferred arrangement of which is illustrated in the accompanying drawings, wherein:

Fig. 1 is a perspective view of a dental cement mixing apparatus embodying the features of the present invention, particularly illustrating the transparent panels of the receptacle.

Fig. 2 is a plan view of the mixing apparatus.

Fig. 3 is a transverse sectional view through the mixing apparatus on the line 3—3, Fig. 2.

Fig. 4 is a horizontal sectional view through the mixing apparatus on the line 4—4, Fig. 3.

Fig. 5 is an end elevation of the mixing apparatus, the receptacle and cover therefor being shown in raised position for removal of the mixing slab.

Fig. 6 is a perspective view of the dehydrating sheet for the receptacle.

Referring more in detail to the drawings:

25 1 indicates a dental cement mixing apparatus which preferably includes a base 2 adapted to carry the principal portions of the apparatus and preferably forming the bottom of a receptacle 3 which may be of any convenient size or shape, but preferably consists of a box-like arrangement attached to the base by hinges 4, and adapted to enclose a suitable glass mixing slab 5. The mixing slab may be of conventional structure as is commonly used for the mixing of dental cement.

30 The receptacle 3 is preferably of rectangular shape and includes front, rear, and side panels 6, 7, 8 and 9 respectively, which are preferably formed of any transparent resin such as phenol 40 formaldehyde, vinyl, methyl metacrylate, cellulose nitrate or acetate, urea, sterines or styrols, or any other transparent substance, such as glass. Metal or other substance may be used for one or more sides and metal corners 10 or the like may be used to attach individual panels together, as at 11 to simplify the structure of the receptacle.

45 The closure of the receptacle is completed by a cover member 12, preferably of transparent material, similar to that used in the walls of the receptacle, said cover being mounted on the receptacle by hinges 13 which connect the rear edge 14 of the cover member with the rear wall 7 of the receptacle, whereby the cover member 55 may be hinged upwardly and rearwardly away

from the operator to open the receptacle and provide access thereto. The transparent cover member has at least one opening for the admission of cement ingredients, but preferably is provided with an opening 15 for liquid ingredients, and slightly removed therefrom an opening 16 for powder ingredients.

In order to provide access to the receptacle for mixing cement, as at 17, on the mixing slab 5, and yet prevent the effect of the surrounding air from penetrating into the receptacle, the front panel 6 is provided with an aperture 18 of substantial size. The aperture 18 is provided with an air seal which includes a flexible diaphragm 19 which may be of thin semi-transparent rubber, but is preferably formed of plasticized vinyl resin or the like to provide the maximum amount of light in the receptacle. The flexible diaphragm 19 is of larger area than the aperture 18 to provide margins 20 superimposed over the panel 6 and is preferably backed by means of a transparent sheet of plastic material 21 which is secured to the panel 6 by means of suitable fastening devices 22. The flexible diaphragm may be secured in a suitable frame and said frame secured to the panel 6 in a conventional manner.

A suitable aperture 23, preferably consisting of a slot is provided in the diaphragm for passage of mixing tools or the like 24 through the diaphragm for manipulation of the cement mix 17 on the glass slab, the diaphragm being adapted to form closely around the tool 24 to provide a substantial air seal and prevent the outside atmosphere from affecting the cement in the receptacle.

In order to maintain the air in the receptacle under proper temperature and humidity conditions, the rear panel 7 is preferably provided with a tubular connection 25 which is connected by a flexible conduit 26 with a suitable source of air, said air being preferably cooled and dehydrated to a proper degree. The conduit 26 is preferably connected to a container 27 preferably having a hygroscopic agent, such as calcium chloride, phosphorous pentoxide, colloidal silicodioxide, or other suitable agent 28 therein, the container preferably receiving air from a suitable compressed air source through a tube 29. The container 27 may be of any desired shape, however, it is shown as tubular, with the hygroscopic agent confined by perforated members 30 and 31 spaced from the ends 32 and 33 of the container. The container shown is attached to the rear portion of the base member by means of a slip spring device 34 for easy removal and replacement. The container may be placed on any convenient portion of the unit and rigidly attached if desired.

In normal climates, there is sufficient humidity in the atmosphere to require a dehydrating agent, particularly in the winter time. Dentist's offices normally have open gas flames therein, which increase the tendency for condensation of moisture on the glass slab. This tendency is also increased since the glass slab is usually cooled prior to the insertion into the receptacle. In some localities where the atmosphere is arid, the lack of humidity speeds the drying of the cement in such a manner that there is insufficient time to properly manipulate and mix same. Under such conditions, the hygroscopic agent in the container 27 should be replaced by a humidifying agent, such as cotton, wet with water, whereby the air passing therethrough would receive sufficient

moisture to prolong the mixing time for the cement in the receptacle.

To prevent excessive moisture from causing condensation on the mixing slab, I have also provided a rigid sheet 35 to which calcium chloride or other hygroscopic agent has been affixed by non-hydrous cement, such as cellulose acetate and acetone, or impregnated in the sheet in any suitable manner. The sheet is preferably of substantially the same length as the interior of the receptacle 3 and is supported at its end by clips 36 having inwardly extending flanges 37 and 38 to provide grooves 39 adapted to receive the ends of the sheet 35, the sheet preferably having an aperture or the like 40 adjacent the tubular connection 25 to permit free entry of air from the container 27.

In order to provide adequate air circulation in the receptacle 3 and proper air flow and contact over the hygroscopic sheet 35, I provide an agitator 41 preferably including a flat member 42 on the end of a rod 43 which extends through an aperture 44 in the wall 8 of the receptacle, said rod 43 terminating in a knob or suitable handling device 45 for easy manipulation and reciprocation of the agitator 41 in a backward and forward motion to cause suitable air agitation in the receptacle. The amount of air agitation aids the control of the condensation in the receptacle regardless of the type of air-conditioning units that might be attached to the tubular connection 25, or whether any unit is attached to the connection.

Strips 46 and 47 are provided on the base 2, at each end of the receptacle 3, to aid the hinges 4 in supporting same on the base and preventing lateral movement thereof. The base is also provided with suitable handles 48 and 49 to provide for easy movement of the apparatus in a dentist's office. These strips and handles as well as the other respective parts of the entire apparatus may be fabricated, piece by piece, or may be partly fabricated and partly molded, or molded entirely, as desired, to provide an attractive and substantial apparatus.

In using an apparatus such as described, and particularly for mixing dental cement, the sheet 35, having a hygroscopic material impregnated or otherwise attached thereto, is inserted in the slot 39 in the receptacle, with the aperture 40 in alignment with the tubular connection 25. The conduit 29 is connected to a suitable air supply and the container 27 is filled with a dehydrating agent 28 or humidifying agent, as indicated and required by the surrounding atmospheric conditions. The conduit also is connected to the flexible conduit 26 whereby the air flows from the conduit 29 through the material in the container 27 to the tubular connection 25, into the receptacle 3 to condition the air therein. The receptacle 3 is then hinged upwardly on the base 2, as shown in Fig. 5, and the glass mixing slab 5, which has been previously chilled in a suitable refrigerator or the like, is placed therein. The receptacle 3 is then hinged downwardly so that the lower edges 50 seat on the upper surface of the base 2 between the strips 46 and 47, and the cover 12 is hinged downwardly to complete the enclosure of the glass mixing slab. After the glass slab is placed in the receptacle 3, powdered cement ingredients are inserted through the cover aperture 16 onto the surface of the slab 5. Suitable quantities of liquid ingredients are then poured through the aperture 15 and worked into the powdered ingredients by means of mixing

tools 24 which are extended through the slot 23 in the flexible diaphragm 19 in the front panel 6, suitable panels of the receptacle being transparent to permit adequate light to enter the receptacle and provide proper observation of the mixing operation. The chilled slab, being confined by the receptacle, tends to retain its temperature for a long period of time, particularly if the air supply entering at the connection 25 is cooled, and there would be substantially no condensation in the receptacle even though the glass slab is chilled, since the moisture is controlled by the material in the container 27. If any condensation does appear on the glass slab in the receptacle, it is easily observed by the operator and with proper manipulation of the agitator 41, the air is circulated past and in contact with the hygroscopic material impregnated in the sheet 5 to further reduce the humidity in the receptacle 3.

After suitable mixing of the cement ingredients, the cover 12 may be lifted to provide access to the receptacle for removal of the cement, easy access to the glass slab also being had to provide for easy removal and cleaning through the open top of the receptacle or by hinging the entire receptacle on the hinge members 4 whereby the slab may be removed from the top of the base member 2, the panel members 48 and 49 permitting easy movement of the apparatus into a suitable cabinet or other storage.

From the foregoing, it is apparent that I have provided an apparatus for enclosing a chilled dental cement mixing slab to reduce interchange of radiant heat, provided for the control of temperature and humidity conditions during the mixing of the cement; and have provided a sturdy, durable and efficient apparatus for the mixing of dental cement.

What I claim and desire to secure by Letters Patent is:

1. In an apparatus for mixing dental cement, a mixing slab, a receptacle for enclosing said slab, said receptacle having at least one transparent panel for providing a view of the interior of the receptacle, a flexible diaphragm panel in the receptacle, and means extending through the diaphragm into the receptacle for mixing the cement on the mixing slab.

2. In an apparatus for mixing dental cement, a mixing slab, a receptacle for enclosing said slab, said receptacle having openings therein for applying cement ingredients to the slab, means for dehydrating the air in the receptacle, and means extending into the receptacle for mixing the cement ingredients on the slab.

3. In an apparatus for mixing dental cement, a chilled mixing slab, a receptacle for enclosing

said slab, said receptacle having openings therein for applying cement ingredients to the slab, means for conditioning the air in the receptacle for reducing condensation of moisture on the chilled slab, and means extending into the receptacle for mixing the cement ingredients on the chilled slab.

4. In an apparatus for mixing dental cement, a mixing slab, a receptacle for enclosing said slab, said receptacle having openings therein for applying cement ingredients to the slab, means for dehydrating the air in the receptacle, a flexible diaphragm panel in the receptacle, and means extending through the diaphragm into the receptacle for mixing the cement ingredients on the slab.

5. In an apparatus for mixing dental cement, a mixing slab, a receptacle for enclosing said slab, said receptacle having openings therein for applying cement ingredients to the slab, a sheet impregnated with dehydrating agents in the receptacle, means for agitating the air in the receptacle for moving same by the sheet to dehydrate the air, and means extending into the receptacle for mixing the cement ingredients on the slab.

6. In an apparatus for mixing dental cement, a support, a rectangular frame hinged to the support and adapted to seat thereon, a cover hinged on the frame and adapted to cooperate with same to form an enclosure, at least one transparent panel in the frame, a mixing slab in the enclosure, and means extending into the frame for engaging the slab.

35 7. In an apparatus for mixing dental cement, a chilled mixing slab, a receptacle for enclosing said slab, said receptacle having openings therein for applying cement ingredients to the slab, said receptacle having at least one transparent panel for providing a view of the interior of the receptacle, means for conditioning the air in the receptacle for reducing condensation of moisture on the chilled slab, a flexible diaphragm panel in the receptacle, and means extending through the diaphragm into the receptacle for mixing the cement on the mixing slab.

8. In an apparatus for mixing dental cement, a support, a rectangular frame hinged to the support and adapted to seat thereon, a cover hinged on the frame adapted to co-operate with same to form an enclosure, at least one transparent panel in the frame, a chilled mixing slab in the enclosure, means for conditioning the air in the enclosure for reducing condensation of moisture on the chilled slab, and means extending into the frame for engaging the slab.

NORTON L. WHEELER.
